UNITED STATES PATENT OFFICE

WILLIAM E. PRINDLE, OF COLUMBUS, OHIO, ASSIGNOR TO THE V-W VENTILATOR COMPANY, OF COLUMBUS, OHIO, A CORPORATION OF OHIO

SCREED HOLDER

Application filed November 6, 1930. Serial No. 493,826.

The present invention is directed to improvements in screed holders designed more particularly for use in connection with cement floor constructions, but is not necessarily limited thereto.

The primary object of the invention is to provide a holder of this character which can be easily and conveniently applied to the cement floor when the floor is in a semi-solid condition, and when the material sets, the holder will be positively held against disengagement.

A further object of the invention is to provide a screed holder formed from a single blank of suitable gage sheet metal, and one which is extremely simple in construction, durable, efficient in operation and which can be manufactured at a very small cost.

With these and other objects in view, as will appear as the description proceeds, the invention consists in the novel features of construction, combinations of elements and arrangements of parts, hereinafter to be fully described and pointed out in the appended claims.

Figure 1 is a side elevation of the device showing it in place in the floor.

Figure 2 is a perspective view of the holder.

Figure 3 is a sectional view on the line 3-3 of Figure 2.

Figure 4 is a top plan view of the holder, and

Figure 5 is a view showing a plurality of holders mounted upon the spacing strip employed for inserting the holders in position within a concrete floor.

The holder is formed from a single length of sheet metal of the desired gage and is bent to provide a pair of vertical arms 1, the lower ends of which being integrally connected by a trough-like member 2. This member has its sides 3 divergently disposed so that the upper edges thereof will be spaced laterally, whereby the member will be substantially wedge shape in cross section. The ends of the sides 3 terminate in substantially triangular plates 4, the upper edges of which being spaced from the lower

adjacent ends of the arms 1 whereby transverse end pockets 5 are provided which communicate with a channel 6 formed between the sides 3.

It will be observed that the lower ends of the arms 5 are longitudinally corrugated, as at 7, to impart to the lower ends of said arms the necessary stability, the corrugations extending to the point above the plane of the member 2 so that the arms may be bent parallel to the member when the holders are engaged in the concrete floor 8. It is necessary at times to bend the upper ends of the arms so that the same will be level with the floor to prevent the same obstructing the passage of wheelbarrows and material during the building operation.

The arms are provided near their upper ends with a plurality of perforations 9 in which securing devices 10 are engaged, said securing devices penetrating the screed 11 to which the floor boards 12 are secured in the usual manner.

Since the member 2 is substantially wedge shape, the holder can be easily forced into the floor when the material is in the semi-solid state, a distance to permit the arms 1 to extend above the floor surface so that when the screeds are placed between the arms, the upper ends of said arms will be in proper position, after which the securing devices 10 are applied, it being of course understood that the screeds are not engaged with the holders until the floor material is set. Owing to the trough-like formation of the member 2, the semi-solid cement will fill the member as well as the pockets 5, thereby positively preventing upward movement of the holders after the cement sets.

It will be observed that the arms 1 are formed from a pliable material, in this instance sheet metal. This permits the arms to be bent outwardly at their upper ends as indicated by the numeral 13. In placing the holders in the soft concrete, I first removably nail or otherwise secure the out-turned ends 13 to the under side of a longitudinal strip. By means of this strip the holders are properly spaced and positioned with respect to each other, and any desired

number of them may be secured in connection with the strip member for the purpose of facilitating and rendering more accurate the placing of the holders in the concrete.

5 After the holders have been properly secured to the strip, the latter is placed over the soft concrete and pressure applied to force the holders into embedded relation within the concrete. Since the latter is 10 usually soft when this is done, no difficulty is encountered, the wedge shaped formation of the lower end of each holder facilitating the insertion thereof. Following the insertion of the holders in the concrete the latter 15 is permitted to harden so as to obtain a secure grip on each holder. Then the board or strip upon which the holders are originally nailed is ripped loose from the arms 13. Since the arms have been bent outwardly 20 as indicated at 13 the same will not interfere with ordinary building operations, that is, they will be flush with the upper surface of the floor and not offer obstacles or impediments upon which builders may trip.

25 It is frequently a matter of weeks before the wooden flooring is laid following the insertion of the screed holders. During this interval said holders are completely out of the way by reason of the fact that they are 30 bent downwardly or outwardly to evenly engage the floor. When the time comes to place the screeds and flooring 11 and 12, the outwardly directed arms 13 are bent upwardly to assume their vertical positions 35 and to be nailed in engagement with the screeds proper. It will be observed that the alignment of the screed holders has been properly and accurately regulated by the fact that such holders are previously properly 40 spaced and aligned at the time they were inserted or imbedded in the concrete.

What is claimed is:

1. A screed holder comprising a pair of arms, a member connecting the lower ends 45 thereof, said member including convergingly arranged sides, said member having pockets at its juncture with the arms.
2. A screed holder comprising a pair of spaced side arms, a member comprising convergingly arranged sides having terminal 50 triangular plates connected with said arms and defining pockets between the arms and ends of said sides.
3. A screed holder comprising a single 55 piece of sheet metal having suitable width and length, said piece being bent into U shaped form with a cross bar connecting the side arms of the U straight and arranged at substantial right angles to said arms, the 60 material forming said cross bar being folded upon itself longitudinally of the bar into U shaped cross sectional formation forming a pocket extending the full length between said arms, said pocket together with the 65 portions thereof located at the juncture be-

tween the arms and bar producing a substantially I shaped outline.

4. A screed holder comprising a single piece of sheet metal formed into a strip and bent to U shaped form, the cross bar of the U 70 being straight and the side arms of the U arranged substantially parallel to one another, the material forming the cross bar being folded upon itself longitudinally of the bar and transversely of the material forming the juncture between the bar and arms giving the bar an I shaped outline when viewed in plan, and a longitudinally extending strengthening rib formed at the lower 75 ends of said side arms.

In testimony whereof I affix my signature.

WILLIAM E. PRINDLE.
